METHOD AND MEANS FOR CORRECTING
INCLINATION IN DRIVING SECTIONAL
SHEET PILING

Everette L. Bowen, Barstow, Md.

Application October 4, 1933, Serial No. 692,207

18 Claims.

(Cl. 61—58)

This application is a continuation, as to all common subject matter, of my prior copending application Serial No. 687,901, filed September 1, 1933. The present invention relates also to the art of hydraulic and earth engineering, being concerned with that phase of the art which has to do with the placing and driving of sectional sheet piling, particularly interlocking metal sheet piling.

10 In the construction of seawalls, bulkheads, cofferdams and the like, it has been found in most cases that ground conditions cause progressively increasing inclination of the piling sections as they are driven home. In wall structures of appreciable length such inclination soon becomes a matter of serious concern, and unless promptly corrected or compensated the inclination becomes so pronounced at the top of the wall that it is difficult and at times impossible to drive succeeding sections without injury to the structure.

Depending on ground conditions the inclination at the top of a wall may be either toward or away from the point of beginning, to right or left of the center line, or as a combination of both. If not checked, especially in the case of piling sections of considerable length, on walls using interlocking metal piling sections the interlock pulls apart at the bottom of the wall and thereby materially weakens the structure, as well as impairing its effectiveness.

An object of this invention is the provision of a method of correcting such objectionable inclination and tendency to inclination as the piling sections are driven. Another object is the provision of means for correcting inclination in sheet piling sections as the sections are driven home. A further object is the provision of sheet piling elements capable of formative adaptation to ground conditions in a manner to correct inclination as the sections are driven home. A still further object is the provision of piling element associated means for building ground resistance in a manner to effect correctional movement of a piling element as it is being driven.

45 Other objects will be apparent to those skilled in the art. The present disclosure is illustrative of structural embodiments of the principles of my invention and it is to be understood that the invention is capable of variation as to details of 50 structure to any extent not inconsistent with the scope of the invention as claimed. In the drawings:—

55 Figure 1 is a perspective view of an interlocking sheet metal piling section and associated inclination correcting means.

Figure 2 is an elevation of the entrant end of a piling section web illustrating the selective association of inclination correcting means therewith for control of correctional movement.

60 Figure 3 is a section on line 3—3 of Figure 2.

Figure 4 is a section on line 4—4 of Figure 3.

Figure 5 is a perspective view of an attaching element employed for connecting a piling element and an inclination correcting member in service relation.

5

Figure 6 is a detached group perspective of the assembly shown in Figures 2 and 3.

Figure 7 is a perspective view of an alternative form of inclination correcting member.

Figure 8 is an elevation of the member shown in Figure 7, as applied in service, and illustrating the use of means for adjusting the angular disposition of the correcting member.

10

Figure 9 is a section on line 9—9 of Figure 8.

15

Figure 10 is a section on line 10—10 of Figure 9.

Figure 11 is a fragmentary perspective view of an alternative form of inclination correcting means.

20

Figure 12 is a horizontal section through the structure of Figure 11.

Figure 13 is a view, partly in section, illustrating an assembly employing an alternative form of securing means.

25

Figure 14 is a perspective view of the alternative form of securing means shown in Figure 13.

Figure 15 is an elevation, partly in section, of a further alternative embodiment of the inclination correcting means.

30

Figure 16 is a perspective view of a piling section as formatively adapted to effect correctional movement of the section as it is driven.

Figure 17 is a transverse section through the lower part of the piling shown in Figure 16.

35

Figure 18 is a perspective view of an alternative manner of formative adaptation of a sheet piling element to effect correctional movement of the section as it is driven.

Figure 19 is a vertical section through the structure of Figure 18.

While this invention is applicable to all piling and particularly to sheet piling, it has perhaps its greatest field of utility in connection with sectional interlocking sheet piling made up of metal sections of the general type as shown in Figure 1 wherein the piling section 20 comprises a flat central web 21, angled shanks 22, and co-extensive jaws 23, all of integral construction.

In wall structures formed of such piling the sections are successively driven in interlocked engagement. Particularly in the case of seawalls

40

inclination becomes apparent after the first few sections are placed and driven home. In the practice of this invention such inclination, when it becomes apparent, is corrected by means of corrective treatment of succeeding piling sec-

45

tions in such manner that as the piling is driven home a ground resistance is built up at the entrant end at such an angle that the piling is moved in the desired direction.

50

Such building up of ground resistance may be

55

60

accomplished by formative adaptation of individual piling sections to local conditions, as shown in Figures 16 to 19. Where the nature of the ground material permits, the desired correctional movement of a section may be obtained by removing a portion of the jaw inwardly from the entrant end, as shown at the left of Figure 16 where the left hand jaw 23 terminates above the bottom of the section to provide a ground pressure building shoulder 24 that acts to force the bottom portion of the section to the right, with respect to Figure 16, as the section is driven home. Similarly, the cutting away of the right hand jaw may be resorted to for moving the section to the left. In cases where a larger area of ground engaging surface is needed to bring about correctional movement the section is further formatively adapted to such condition by striking over the portion 25 of the shank 22 between the shoulder 24 and the bottom edge of the section web 21 along a line of bend 26 procured by preliminary blow torch heating. As seen in Figure 17 the result of this operation is to provide an inclined bearing member 25 that extends laterally of the web 21 to engage the ground at an angle opposed to the angle of section inclination.

As shown in Figures 18 and 19 a piling section may be formatively adapted to correct a leaning to one side of the center line by striking out an inclined lip 27 at the bottom of the web 21 to a desired degree of inclination whereby the lip is angled with respect to the section web in a manner to build up ground resistance as the section is driven, and thereby to force the web into correctional movement at the bottom of the piling. In Figure 19 the dotted line showing of the lip 27 indicates the selective disposition of this element where lateral movement of the web in an opposite direction is desired.

The necessary building up of ground resistance to effect correctional movement may also be accomplished through the agency of ground engaging guide means that may be attached, as needed, to the entrant portion of a piling section. An embodiment of such means is shown in Figures 1 to 6 and comprises a substantially U shaped metal guide member 28 having a bend 29 and upright arms 30 terminating in ears 31 apertured in transverse alignment to receive the cylindrical shank 32 of a securing element here shown as a pivot pin 33 having at one end an enlarged head 34 and a central reduced neck 35 formed by an arcuate cut out in the body of the shank. The piling web 21 is provided with a transverse cylindrical bearing aperture 36 of a size sufficient to receive the securing pin shank therethrough, the aperture being preferably located in the longitudinal median of the piling web. This bearing aperture is so positioned that its distance above the bottom edge of the web is appreciably less than the length of the arms of guide member 28 so that when the parts are assembled, as shown in Figures 2 and 3, the guide is pivotally attached to the piling section and may be swung selectively to a plurality of variously angled positions with respect to the transverse median plane of the web as shown in dotted lines in Figure 2. In assembling the parts the guide is disposed from beneath with its arms 30 extending upon opposite side faces of the piling web and the shank of pin 33 is passed laterally through the ears and web aperture whereupon the guide member drops down on the pivotal bearing provided by the reduced neck 35 of the

pin shank with the shoulders formed in the shank at each end of the reduced neck engaging against the sides of the web to anchor the pin against lateral dislodgment.

Figures 13 and 14 disclose an alternative embodiment of securing pin 33' having a head 34' at one end and which differs from pin 33 only in that its shank 32' has a central full diameter portion extending substantially the width of the piling web 21, with arcuately reduced portions 35' on either side thereof to engage in the ears 31 of the guide member whereby to permit the ears to drop down on the bearings thus provided and anchor the pin against lateral dislodgment.

Figures 7 to 10 illustrate an alternative embodiment of ground engaging guide means consisting of a metal bar 37 formed with a flat inner straight edge from which there extends at the top portion a lateral cylindrical shank 38 having an internal arcuately reduced neck 39. At its bottom the bar is provided with a hook portion 40 adapted to extend beneath the bottom edge of a piling web and which terminates in an upwardly directed bill 41 substantially in vertical alignment with the outer end of the shank 38. The bill 41 is spaced from the shank a distance sufficient to permit of the guide member being moved laterally to pass the shank 38 through the piling web aperture with the bill passing beneath the web bottom, whereupon the member drops down on the bearing provided by the reduced neck 39 to anchor the shank against lateral dislodgment.

Figures 11 and 12 are directed to an alternative construction of guide means particularly effective in correcting any leaning to one side of the center line of a wall. In this form the guide comprises a substantially U shaped body similar to that shown in Figure 6, having upright parallel arms 30' and a bend 29'. The body is provided with an integral fin extending laterally from each side face of the body at the bend 29', which fin is designated as 42 and which is disposed at an angle with respect to the bend 29' and one of the arms 30'. In this instance the fin structure 42 functions as does the lip 27 as shown and described in connection with Figures 18 and 19.

In all forms of the attachable guide means substantially the entire extent of the outer edge of the body is shaped as a rib beveled on its opposite side faces, the remainder of the body being of substantially rectangular cross-section at the arms, bends, and bar, hook and bill respectively. This construction facilitates ground engagement. In some instances it may be desirable to insure that the guide member first engages the ground material in substantially a vertical position. In Figure 15 is shown a further alternative embodiment of ground engaging means incorporating this principle. It consists of a substantially U shaped guide member similar to the form shown in Figure 13 in all respects except that its bend 29'' is angularly offset with respect to the arms 30'' so that when the guide is swung to engage the bend against the bottom edge of the piling section web 21 the arms 30'' will be disposed at the desired angle for correctional movement of the section and the bend 29'' will extend beneath the section for entering the ground substantially in vertical position.

In all structural embodiments of this invention the inclination correcting means comprises a ground engaging guide associated with a piling element. The guide is angled in opposition to the angle of inclination which is to be corrected, and it is so formed and disposed that as the piling

element travels down under driven movement the angled body of the guide builds up ground resistance thereunder in a manner to cause the entrant end of the piling to move in the desired direction.

The dotted line position of the guide at the right of Figure 2 illustrates one of the two extreme positions of the guide in service, with the bend of the guide body contacting the bottom edge of the piling web. As it is not at all times desirable to utilize the maximum shifting effect of the guide means I have provided a means of controlling the angled adjustment of the guide, which means consists of a series of spacer elements in the form of different sized wedge blocks 43, 44 and 45. These blocks are of graduated degrees of thickness and are adapted to be interposed between the bend of a guide member and the bottom edge of the piling web, as shown in Figure 2, the thickness of the particular spacer wedge selected determining the angular adjustment of the guide.

In the various figures of the drawings like reference characters have been employed to indicate identical parts in support of particular and general description.

I claim:—

1. In combination, a piling element, a ground engaging guide member carried thereby and movable thereon, and means interposed between said piling element and guide member for selectively angling said guide on the piling with respect to its line of driven movement.

2. In combination, a piling element, a ground engaging guide member movably mounted thereon and having a portion extending beneath the piling element bottom, a spacer block having opposed faces respectively contacting the piling element bottom and the extending portion of the guide member, and one face being angled with respect to the other.

3. In combination, a piling element, a ground engaging guide angularly adjustable thereon, and means interposed between and cooperatively engageable with said guide and piling element to determine the angular adjustment of the guide.

4. In combination, a sheet piling section, a ground engaging guide carried thereby and having a body portion angled with respect to the axis of the section, and said guide having an entrant portion substantially parallel to the axis of the section.

5. Inclination correcting means for sheet piling sections, comprising a ground engageable bearing member, and means for swingably attaching said member to the entrant end of a piling section whereby said member may be angled with respect to a section after it is attached thereto.

6. The combination with a piling element having an entrant end adapted to be driven into the ground, of a ground bearing member carried by said element, and means on said member engageable beneath said entrant end at an angle thereto.

7. The combination with an interlocking sheet piling section having a web, shanks, and jaws, of a ground bearing member pivotally attached to said web and having a portion disposed beneath the entrant end thereof, and said member having a body portion extending laterally of the web and substantially perpendicular thereto.

8. In combination, a sheet piling section, a

ground engageable guide plate carried thereby, and said plate having a portion extending over the entrant edge of said piling section at an angle with respect to the vertical median plane of the section.

9. In combination, a sheet piling section having a web provided with a transverse aperture, a ground engaging guide member, and means for pivotally securing said guide member to the web, said means comprising a pivot pin associated with said guide and having a bearing in the web aperture.

10. In combination, a sheet piling section having a web provided with an aperture, a ground engaging guide member, a pivot pin associated with said guide member and journaled in said web aperture, and a shoulder on said pin engaging said web to anchor the pin against lateral dislodgement.

11. In combination, a sheet piling section having a flat web portion provided with an aperture, a substantially U shaped ground engageable guide member engaged therewith with its bend beneath the bottom edge of the section, the arms of said U shaped member terminating in ears apertured in alignment with the web aperture, a securing element disposed through said ears and web aperture, and said securing element having a rounded portion cooperating with the web aperture to provide a pivotal bearing for the guide member.

12. In combination, a sheet piling section having a web provided with an aperture, a ground engaging guide member having a hook portion extending beneath the bottom edge of the web, and a pivot pin extending from said guide member in and through the web aperture.

13. In combination, a sheet piling section, and a ground engaging guide member pivotally attached thereto.

14. Piling element inclination correcting means comprising a ground engageable guide member formed to engage over the bottom edge of a piling element, and piling element engageable securing means on said guide member.

15. In combination, a piling element having a ground entrant edge, a ground bearing guide member extending across said edge in advance thereof, and means pivotally connecting said guide member and piling element.

16. In combination, a piling element having a ground entrant edge, and a ground bearing guide member extending across said edge in advance thereof at an angle with respect to the axis of the piling element.

17. The combination with an interlocking sheet piling section having a web, shanks, and jaws, of a ground bearing member pivotally attached to said web in the median plane thereof, a fin on said member and extending laterally of the web, and means on said member for engaging the bottom edge of the web at one side of its median plane.

18. The method of correcting inclination in piling elements during a driving operation, which consists in placing a ground bearing guide over and across the bottom edge of an inclining element prior to ground entry, attaching the guide permanently to the element, then setting the guide at an angle opposed to the angle of inclination of the element, and thereafter driving the element home.

EVERETTE L. BOWEN.
